B. Singer, Atty.

UNITED STATES PATENT OFFICE.

WILLIAM HENRY JOHNS, OF REIGATE, ENGLAND.

LOUD SPEAKER FOR USE IN WIRELESS TELEPHONE APPARATUS.

Application filed March 27, 1924. Serial No. 702,885.

To all whom it may concern:

Be it known that I, WILLIAM HENRY JOHNS, a subject of the King of Great Britain, and resident of Reigate, in the county of Surrey, England, have invented certain new and useful Improvements in and Relating to Loud Speakers for Use in Wireless Telephone Apparatus, of which the following is a specification.

10 This invention relates to loud speakers for use in connection with wireless apparatus.

One object of the invention is the provision of an improved magnet for vibrating the sound producing diaphragm.

15 Another object is the provision of an improved loud speaker which will be simple and durable of construction.

Other objects and advantages will appear hereinafter.

20 A loud speaker in accordance with the invention is illustrated in the accompanying drawings and the same will now be described it being understood that the particular construction illustrated is susceptible of various modifications without departing from the scope of the appended claim.

In these drawings:—

Figure 1 is a sectional elevation of the loud speaker (minus the horn),

30 Figure 2 is a plan of the same but with the horn connection member and the diaphragm removed, and Figure 3 is a perspective view of the same.

Referring to the drawings, the sound reproducing parts of the loud speaker are all contained in a non-magnetic cylindrical housing 1 supported by means of three legs 2 and adapted to support the horn (not shown) through the medium of a connection member 3 which will be more particularly described hereinafter.

40 The said sound reproducing parts consist of the usual magnetic diaphragm 4 secured over the open upper end of said housing 1 between the latter and the connection member, and an electromagnet, indicated generally by the numeral 5, for effecting vibration of the said diaphragm. The cores of this electromagnet consist of two sets 7 of magnetic laminations which are respectively secured to two magnetic blocks 8, by means of clamping brackets 8^a said blocks 8 being mounted at opposite ends of a magnetic base plate 9. The cores 7 are, in the usual man-

55 ner provided with respective windings and these windings are adapted to be energized by way of the usual terminals 11.

The whole electromagnet above described is supported adjustably in such manner that the pole pieces 6 can be moved, within 60 limits, nearer to or further from the diaphragm 4; and the support by which this is adapted to be effected will now be described.

Depending vertically downwards from the centre of the base plate 9 and passing 65 through a bossed hole 12^a in the closed lower end of the housing 1 is a brass or other non-magnetic adjusting pillar 12. This pillar is rigidly secured to the base plate 9 by means of a nut 13 and spring washer 14, as 70 shown, and is prevented from rotating, while being free to slide axially in the hole 12^a, by means of a stud 15 engaging in a vertical slot 16 in one side of the said hole. The lower end of this pillar 12 extends to 75 the outside of the housing 1 and the extending portion is screw-threaded and has screwed thereon an adjusting wheel 17 the centre boss of which is adapted to abut (with a washer 18^a in between) against the 80 boss 18 of the hole 12^a.

The adjusting wheel 17 is prevented from being screwed right off the pillar 12 by means of a retaining screw 19.

From the above it will be seen that the 85 position to which the wheel 17 is adjusted on the adjusting pillar 12 determined the highest position to which the electromagnet 5 can be moved. The electromagnet is permanently retained at such highest position 90 by means of a non-magnetic spring support 20 beneath the plate 9 which permanently biases the electromagnet in the upward direction. The electromagnet can thus be raised or lowered at will by rotation of the wheel 17. The extreme upward limit to which the electromagnet can be adjusted is determined by the screw 19 limiting the downward adjustment of the wheel 17, and the extreme downward limit to which the magnet can be adjusted is determined either by the support 20 coming to rest on the boss 18 or else by the wheel 17 arriving at the upper end of the screw thread on the pillar 12. 100 105

The aforesaid connection member 3 is made of some non-magnetic material of high specific gravity and is secured, with

the diaphragm 4 in between, to the housing 1 by means of screws 21, which pass loosely through slots 22 in the said diaphragm. The connection member thus securely clamps the 5 diaphragm in position without any danger of the latter being distorted.

The form of the connection member is clearly shown in the drawing. Outwardly it is trumpet shape, having a reduced spigot 23 at its smaller and upper end on which the horn is adapted to be fitted. At 24 the said member is cut away as shown so as to give freedom to the diaphragm 4 in vibrating, and a hole 25 affords communication 10 between said cut away portion and the horn. This hole is of taper formation being larger at its upper than at its lower end, and at its said lower end it merges into the cut 15 away portion 24 by way of a smooth curve 20 as shown.

What I claim and desire to secure by Letters Patent is:—

In a loud speaker for use in connection with wireless apparatus an electromagnet for vibrating the diaphragm, said electromagnet comprising an elongated rectangular base plate of magnetic material having its plane parallel to the diaphragm, separate blocks of magnetic material mounted at two opposite ends of said base plate on 25 the side thereof facing the diaphragm, laminated pole pieces and clamping brackets whereby said pole pieces are mounted respectively on said blocks on the sides thereof remote from said base plate and whereby the 30 laminations of said pole pieces are bound together substantially as specified.

In witness whereof I affix my signature.

WILLIAM HENRY JOHNS.
